UNITED STATES PATENT OFFICE.

ROBERT L. LYONS, OF WALTHAM, MASSACHUSETTS.

STITCH-FORMING DEVICE FOR SEWING-MACHINES.

No. 856,645.

Specification of Letters Patent.

Patented June 11, 1907.

Application filed December 12, 1904. Serial No. 236,508.

To all whom it may concern:

Be it known that I, ROBERT L. LYONS, of Waltham, in the county of Middlesex and State of Massachusetts, have invented certain new and useful Improvements in Stitch-Forming Devices for Sewing-Machines; and I hereby declare that the following is a full, clear, and exact description of the same, reference being had to the accompanying drawings, forming a part of this specification.

This invention relates to improvements in stitch forming devices for single thread sewing machine which are particularly adapted for sewing on buttons.

15 The main object of this invention is to so construct a single thread sewing machine for forming groups of stitches by vibrating the work with respect to the path of the needle that the drawing away from the path of the 20 needle of the first of any particular pair of loops is prevented.

Another object of this invention is to so 25 construct a single thread button sewing machine, in which the button and the material to which it is to be sewed is vibrated to alternately present the holes of the button in the path of the needle, that the loop may be cast off the looper without danger of cutting the thread, and a new loop taken from the needle 30 by the looper.

Other objects of the invention will appear from the description and claims.

The invention consists in a sewing machine comprising a needle, a looper, means for 35 vibrating the work with respect to the path of the needle, and a device for preventing the distortion or displacement of the thread loop on the looper, whereby said loop may be in position to receive the next succeeding loop, 40 carried to the looper by the needle, and may be cast off thereonto.

The invention also consists in such other 45 novel features of construction and combination of parts as shall hereinafter be more fully described and pointed out in the claims.

Figure 1, represents a side elevation of 50 portions of the improved sewing machine, partially in section. Fig. 2, represents an enlarged bottom plan view of the same. Fig. 3, represents an end elevation, partly in section, of the same. Figs. 4, 5 and 6, represent diagrammatic views of the needle, the looper and the thread positioner, illustrating successive steps in the operation of these 55 parts in the sewing of a button to fabric.

Fig. 7, represents a bottom plan view of parts of the bed plate showing the needle hole and the thread positioner approximately in the position it occupies with relation to the needle hole when the thread positioner is holding the loops against lateral movement.

Similar numbers of reference designate corresponding parts throughout.

In button sewing machines in which the button, and the fabric, is vibrated with respect to the path of the needle, either back and forth, as in sewing a two hole button, or diagonally for the sewing of a four hole button: whereby the holes of the button are successively positioned in the path of the needle there is a tendency to effect a lateral drag on the loop of thread about the looper to distort said loop, whereby one side of the loop is brought to a position to be caught and broken by the hook of the looper. Or the loop on the looper may be so drawn to one side that it cannot be cast off by the looper on to the next succeeding loop as this latter is being engaged by the point of the looper.

As shown in the drawings 10 represents the bed plate of a button sewing machine on which is mounted the frame 11 having the head 12 in guides of which the needle bar 13, carrying the needle 14 is free to slide. The needle bar 13 is driven from the shaft 15 which is journaled in bearings of the frame 11 and its head 12, and is pivotally connected with the needle bar by the usual connecting rod 16 pivotally connected with a member on said shaft and with the stud 17 adjustably mounted on the needle bar, whereby the rotation of the shaft 15 effects the reciprocation of the needle bar. The usual guide eyes 18 and 19 are secured to the head 12 and serve to guide the thread *a* to the needle.

On the bed plate 10 is movably mounted the button clamp 20 of any usual construction and adapted to be driven in any well known manner to successively position the holes in the button in the path of the needle. In the preferred form shown herein the button clamp 20 is caused to vibrate back and forth, for the positioning of a two hole button, by the lever 21 which is pivotally mounted beneath the bed plate 10 and is pivotally connected at one end with the stud 22 of the button clamp 20, the other end of said lever being furnished with the bearing 23 and with the spring 24 which exerts a drawing strain on this end of said lever. The bed

plate 10, beneath the needle position, is furnished with the usual needle passage as is shown in Figs. 4, 5, 6 and 7.

The main shaft 25 is journaled in bearings 5 of the bed plate 10 and has the cam 26 and the worm 27, this shaft being driven in any usual and well known manner. Adjacent to this main shaft 25 is rotatably mounted the gear 28 the teeth of which are engaged with 10 and driven by the worm 27 to rotate this gear and its cam member 29 the peripherally disposed teeth of which work against the bearing 23 to effect the vibration of the lever 21 against the action of the spring 24 and 15 cause the movement of the button clamp.

Rotatably mounted at the under side of the bed plate are the bevel gears 30, 31, and 32, motion being imparted to the gear 30 by connections with the main shaft 25 to drive 20 said gears and the shaft of the looper 33, of any ordinary construction, which shaft is journaled in bearings of the bracket 34 depending from the bed plate, and is provided with the gear 35 meshing with the gear 36 on 25 the shaft of the gear 32. The looper being so positioned beneath the needle hole of the bed plate that a loop of thread carried down through said hole, by the needle, may be engaged by the hook end of the looper.

30 In the under side of the bed plate is formed the guide 37 extending longitudinally of the bed plate at one side of the needle hole as is indicated in dotted lines in Fig. 2; in this guide is mounted the slide 38 having at its rear end the cam slot 39, extending at an angle with the general extension of the slide, and, in its lower surface a recess 40 having the shoulders 41 and 42, and in this recess is pivotally mounted the arm 43 furnished with the hook end 44. To effect the 40 reciprocation of the slide 38 from the main shaft 25, I provide a lever 45 which is pivotally mounted at the under side of the bed plate and has the pins 46 and 47, the pin 46 being engaged in the slot of the cam 26 while the pin 47 works in the slot 39 of the lever 38.

Beneath the bed plate and adjacent to the slide 38 are, preferably, adjustably mounted 50 the plates 48 and 49, the plate 48 having the stop pin 50, while the plate 49 is furnished with the spring buffer 51. As will be seen by reference to Fig. 2 of the drawings, the finger 43 is moved back and forth between the pin 50 and the buffer 51 and, if this pin and buffer are suitably adjusted, is intercepted by such parts and caused to swing on its pivot. When said finger strikes the spring buffer 51 it is supposed to have engaged the loop of thread between the work and the looper as is shown in Fig. 7 and the main purpose of the buffer is to effect the swinging of the arm 43 to carry its hook end 44 past the needle hole and to a position for 65 holding the thread loop against the drag of

the work and in a position where the hook of the looper will not pass outside said loop, in rotating, and engage with and break the loop. By the use of the spring buffer a yielding strain may be exerted on the arm 43 70 which will not break the thread.

It is to be understood that this improvement is particularly designed for use in a single thread sewing machine, and preferably in such a machine in which the button clamp 75 is vibrated to successively present the holes of the button in the path of the needle.

Attention is now called to Fig. 4 of the drawing in which it will be seen that the needle is on the upward movement after having 80

passed down through the hole *c* of the button *b* to deliver the loop to the looper 33, if now the button be moved to the right in said figure, to bring the hole *d* in the path of the 85 needle, the tendency is to draw the loop of thread in the same direction then carrying the side *a'* of said loop across the path in which the hook end of the looper moves, so that, as the looper rotates to take the loop of thread delivered by the needle through the hole *d* of the button the hook end of the 90 looper will pass outside of the side *a'* of the first loop and will break the same. The slide 38 is timed to move forward as soon as the 95 needle has moved upward sufficiently to clear the arm 43 and the loop of thread is engaged by the hook end 44 of said arm, as the arm 43 strikes the spring buffer 51 said arm is swung approximately to the position shown in Fig. 7, holding the loop of thread approximately 100 as shown in Figs. 5 and 6 and preventing the dragging of the loop, or its distortion, by the movement of the work. As will be seen by reference to Figs. 5 and 6 the looper may now 105 rotate and take the next succeeding loop, delivered by the needle through the hole *d* of the button, without breaking the first mentioned loop, and this latter loop will then be cast off on to said second loop. After the 110 needle 14 has delivered the second loop to the looper 33, through the hole *d* of the button, the needle again moves upward to a point above the button and the slide 38 is moved 115 backward to the position shown in Fig. 2 of the drawings. The button *b* being then moved by the button clamp to again bring the hole *c* in the path of the needle.

I have shown herein a button clamp having preferably a back and forth movement, as is ordinarily used in the sewing of buttons having two holes but I do not intend by this illustration and description to limit my invention to such use for I am well aware that the invention is applicable and useful in machines for sewing on buttons having more than two holes and in which the movement of the button clamp is such that all the holes in the button are presented in succession, in the path of the needle, as is well known in the art. Nor do I desire to limit myself to 130

the specific construction of the thread, or loop, positioner or to the manner in which it is operated.

It is obvious that one of the important features of this invention is to so control the thread loop on the looper that the looper may cast the same off on to the next succeeding loop without reference to the position to which the work, or the button may have been drawn, and this invention is not limited to any particular means for accomplishing this object.

Having thus described my invention, I claim as new and desire to secure by Letters 15 Patent.

1. In a single thread button sewing machine, the combination with a button clamp mounted for movement to position the holes of the button with respect to the needle, of a 20 needle, needle driving means, a looper, and a movable needle thread positioner adapted to engage the thread between the looper and the work to resist the drawing action of the button clamp, in its movement, on the loop.

25 2. In a single thread button sewing ma-

chine the combination with stitch forming mechanism comprising a needle and a looper, of a work holder movably mounted with respect to the path of the needle, and movable means, adapted to engage the thread beneath the work holder, to resist the lateral movement thereof under the action of the work holder.

3. In a single thread button sewing machine, the combination with a button clamp 30 mounted for movement to position the holes in the button with respect to the needle, of a needle, needle driving means, a looper, a needle thread positioner movably mounted to work beneath the work and having a path of 35 movement across the needle path, and means for actuating said positioner to move the thread laterally at alternate loop delivery movements of the needle.

In witness whereof I affix my signature in 40 presence of two witnesses.

ROBERT L. LYONS.
